Patented Nov. 14, 1922.

2 SHEETS—SHEET 2.

UNITED STATES PATENT OFFICE.

GEORGE FROELICH, OF TWO RIVERS, WISCONSIN.

TABLE EXTENSION.

Application filed May 2, 1922. Serial No. 557,930.

To all whom it may concern:

Be it known that I, GEORGE FROELICH, a citizen of the United States, and resident of Two Rivers, in the county of Manitowoc and State of Wisconsin, have invented certain new and useful Improvements in Table Extensions; and I do hereby declare that the following is a full, clear, and exact description thereof.

10 The invention relates to extension tables of a type in which the sections come up automatically on the movement to extended position, the sections being subsequently lowered conveniently for the restoration of 15 parts to their normal position.

It comprises slides, a plurality of cams pivoted to one of said slides, a raising angle secured to the other slide, and a link pivoted at its ends to succeeding pairs of cams 20 and carrying a hook adapted to cooperate with the raising angle for elevating the sections. The pairs of cams operate in sequence so that the sections are elevated one after another as the table is extended. A 25 rod is secured to the link by means of a cable and the tension of the cable by means of the rod causes the collapse of the sections so that the table may be returned to normal position.

30 Objects of the invention are automatic action, the leaves coming up in sequence as the table is drawn apart, securing the elevated leaves in suitable position, the obviating of the inconvenience of tables now in use, which necessitates a searching around for lost leaves when it is desired to extend the table and the putting away of leaves when the table is shortened; quickness of 35 operation and general convenience, the table 40 being extensible without taking off the table spread, dishes, or any other load.

An important object of the invention is the efficiency of the lifting action. The hooks are brought in contact with the raising angle and elevate the sections by the rotation of the cams. In this operation but little friction is developed and but little force need be exerted.

An object is the convenience of lowering 50 action by the more manual movement of the rod. The cams are all rotated and the sections are brought down immediately without the development of friction or any tendency of the sections to stick or jam.

55 With the above and other objects in view, which will appear as the description pro-

ceeds, my invention resides in the novel construction, combination and arrangement of parts, substantially as hereinafter described and more particularly defined by the appended claims, it being understood that such changes in the precise embodiment of the herein disclosed invention may be made as come within the scope of the claims.

In the accompanying drawing, I have 65 illustrated one complete example of the physical embodiment of the present invention constructed according to the best mode I have so far devised for the practical application of the principles thereof, and in 70 which:

Figure 1 is a side elevation of an embodiment of the invention.

Figure 2 is a longitudinal, vertical section thereof taken on the line 2-2 of Figure 3.

Figure 3 is a bottom plan.

Figure 4 is a side elevation of the table in contracted position.

Figure 5 is an enlarged detail showing 80 the cooperative relationship of the cams, the links and the raising angle, and

Figure 6 is a cross section on the line 6-6 of Figure 5.

The transverse frame members 10-10' 85 are secured to end members 11-11', which are curved at the corners and thus brought into engagement with the ends of frame members 10-10'. A metallic angle 12 is secured to frame members 10-10' and by 90 means of screw 13 removably retains legs 14 in position. The frame members 10-10' and end members 11-11' are rigid with major table top 15 and minor table top 15'. Rigidly secured to frame member 10 are 95 metallic male slides 16-16', spaced slightly below major top 15. Metallic female slides 17-17' are rigid with frame member 10'.

As shown in Figure 6, the slides are substantially rectangular in cross section, but 100 are cut away at adjacent sides to form longitudinal flanges. Depending longitudinal flange 18 on the female slides 17-17' have pivoted thereto a series of cams 19. On each side of the table are a pair of these 105 cams adapted to cooperate with each of sections 20, 21, 22, and 23, so that there are four cams to each section. Links 24 have their ends pivotally secured to the lower ends of each pair of cams 19. Rigid with 110 the inner ends of links 24 are depending hooks 25. Male slides 16-16' have raising

angles 26 secured thereto, projecting laterally therefrom.

In elevating the sections, the ends of the table are drawn apart. In this movement 5 the hook 25 on the link 24 positioned below section 20 comes in contact with raising angle 26, which is secured at the extreme end of the male slide. This retains link 24 momentarily, causing cams 19 to rotate on 10 their pivots and lift table section 20 to elevated position. In the upward movement of the table section, screws 27, one of which is secured to each end of the sections, move upwardly, their heads 28 traveling in chambers 29. When the sections are in elevated 15 position the heads are at the ends of the chambers so that there can be no further upward movement. The elevated section, or sections, are then retained incapable of tipping by reason of the pair of cams on each end and the screws 27 so that there is no danger of collapse.

The point of contact of cams 19, with 25 respect to the table sections, has such a relationship to the pivots on which the cams move that there is no tendency for the cams to reverse their movement and drop the sections. The movement of the cams, produced by the retention of hook 25 by raising angle 30 26, is limited owing to the fact that the hook is gradually elevated as the cams rotate on their pivots. Thus on sufficient rotation of the cams the hook is disposed above the raising angle 26. Further rotation of 35 the cams is prevented by stop 35. Figure 5 brings out the relationship of parts, which results in the elevating of hook 25 above raising angle 26.

To each of the links 24 an eye 30 is suitably secured which grips a cable 31 extending therethrough. The length of the cable between the eyes is substantially the distance between the eyes when they have the relationship indicated in Figure 2.

45 There is one of these cables 31 for each side of the table and it extends rearwardly and is secured to a U-shaped rod 32, the arms of which are directed through frame member 10', the movement inwardly of the 50 rod being limited by member 10'. The rod is normally invisible being concealed by end member 11'. When section 20 reaches the elevated position, cables 31 extending to rod 32 are tensioned so that cams 19 are incapable of further rotation in clockwise direction, looking at Figure 2.

It will be apparent, therefore, that section 20 is maintained securely in elevated position. If it is desired to also have section 60 21 elevated, the table is moved further, bringing the hook 25 in engagement with raising angle 26, rotating the cams 19 and raising the section. After any desired number of sections has been raised, the ends 65 of the table may be moved towards each

other slightly to take up any looseness or spacing apart of the sections. Hook 36 is elongated to cooperate with the angle to prevent reverse movement of the cams.

In lowering the sections, rod 32 is moved 70 outwardly, tensioning cables 31 which move the links in the direction of the rods and drop all of the elevated sections simultaneously. The ends of the table may then be moved towards each other and the sections 75 are carried to the position shown in Figure 4, moving between male slides 16-16' and top 15. On the tensioning of the cables 31, the cams are rotated, as described, until they are brought in contact with stops 80 35, which limit the rotation of all of the cams. By means of these stops therefore, the hooks 25 are prevented from moving so far upwardly as not to engage with raising angle 26 when the table ends are again 85 moved apart for raising the sections. When the table is extended, top 15 is supported in the middle of the table by blocks 34 carried by female slides 17-17'. When the parts are in the position shown in Figure 4, 90 top 15 is supported by the sections.

The table sections may be provided with reinforcing means, such as steel shoes, adapted to ride over the cams.

I claim:—

1. In an extension table, the combination of a male slide, a female slide, a plurality of table sections, a pair of cams pivoted to one of said slides for each of said sections, a link having each of its ends pivoted to the lower end of one of said cams, a rigid member secured to the other slide, and means on said link cooperating with said rigid member for elevating one of said sections.

2. In an extension table, the combination of a male slide, a female slide, a table section, a pair of cams pivoted to one of said slides, a raising angle secured to the other slide, a link having its ends pivotally secured to the lower ends of said cams, and a hook on said link cooperating with said raising angle for elevating said table section.

3. In an extension table, the combination of a male slide, a female slide, a plurality of table sections, a pair of cams pivoted to one of said slides for each of said sections, a link for elevating each of said sections having its ends pivotally secured to the lower ends of a pair of cams, a rigid member on the other slide, means for each table section cooperating with said rigid member and said cams for elevating a table section, and manually operable means for lowering all of said table sections simultaneously.

4. In an extension table, the combination of a male slide, a female slide, a plurality of cams pivoted to said female slide, a plurality of table sections, a link pivotally secured to the lower end of a pair of said cams, a rigid member on the other slide,

means cooperating with said rigid member and said link for elevating the table section, and a cable secured to said link for lowering said table section.

5 5. In an extension table, the combination of a table slide, a pair of cams pivoted thereto, a link pivotally secured to the lower ends of said cams, a cable secured to said

link, and a U-shaped rod having an end secured to said cable.

In testimony that I claim the foregoing I have hereunto set my hand at Two Rivers, in the county of Manitowoc and State of Wisconsin.

10

GEORGE FROELICH.
